JOSEPH DUPLESSIE, OF PROVIDENCE, RHODE ISLAND, ASSIGNOR OF ONE-HALF TO
GEORGE F. ROOKE, OF PROVIDENCE, RHODE ISLAND.

GRINDING-FIXTURE.

1,384,726.

Specification of Letters Patent. Patented July 12, 1921.

Application filed November 15, 1919. Serial No. 338,161.

To all whom it may concern:

Be it known that I, JOSEPH DUPLESSIE, a citizen of the United States, residing at Providence, in the county of Providence 5 and State of Rhode Island, have invented new and useful Improvements in Grinding-Fixtures, of which the following is a specification.

This invention relates to grinding fixtures 10 used for shaping and dressing the working or cutting faces of grinding wheels.

Some of the objects of the invention are: to simplify the construction of devices of the character mentioned; to produce a device 15 which embodies means for accurately effecting the setting of the cutting tool or diamond-tool; to produce a simple device with which grinding wheels may be operated upon to either "concave" or "convex" 20 their working or cutting faces or to dress the working faces of grinding wheels parallel to their axes. With the foregoing and other objects in view the invention resides in the particular provision and arrangement of parts more fully described in the 25 following specification and illustrated in the accompanying drawing, in which:

Figure 1 is a sectional side elevation of the device.

Fig. 2 is a plan view thereof.

Fig. 3 is an end elevation thereof.

Fig. 4 is a diagrammatic view, illustrating the setting of the diamond-tool when employed for concaving the cutting face of 35 a grinding wheel.

Fig. 5 is a diagrammatic view, illustrating the setting of the diamond-tool when employed for convexing the cutting face of a grinding wheel.

In the use of the present invention, it is 40 contemplated to move the grinding wheel toward and from the device; particularly with respect to the diamond-tool, and it is also contemplated to move the said tool 45 relatively to the cutting face of the grinding wheel in the shaping and dressing operations.

Referring now to the drawing, it will be seen, that the device is to include a base 50 10, which is movable over a plate 11, by the use of a centering and pivot pin 12 carried by the base 10. A post 13 is provided and this post has a bore 14 which accommodates the enlarged portion of the pin 12. The 55 post 13 is also provided with a small bore

15 which receives the protruding end of a small pin 16 secured to the base 10. The post 13 has a face 17 and this face 17 is in exact alinement with the axial center of the pin 12. 60

The diamond-tool is supported and its movement is effected by parts whose construction and correlation will be presently described. A post 18 is secured to the base 10 by a screw 19. The base 10 is provided with a boss which is provided with a recess which receives the lower end of the post 18. The post 18 is provided with a small bore 20 which receives the protruding end of a pin 21 secured to the base 10. The diamond-tool is carried by a holder 22, which is arranged for sliding movement in a bore in the upper end of the post 18. The holder 22 embodies a lug 23, the purpose of which will appear. The diamond-tool is designated by the numeral 24 and as stated is carried by the holder 22. In the present instance the holder is shown as being constructed of two parts; a part 25 which carries the tool 24 and a part 26 which carries 70 the lug 23. Set screws 27 serve to hold the parts 25 and 26 together.

The setting of the diamond-tool is effected by the use of an adjusting element 28 which has screw threads that coact with the screw threads of a bore 29 in the post 18. The element 28 is provided with a manipulating head 30 which has one face thereof provided with twenty-five graduations 31. The threads embodied by the element 28 are forty to the inch. The head 30 is so constructed as to provide an annular portion 32 which is received by a groove 33 in the end of the part 26 of the holder 22, and it therefore follows, that movement 95 may be imparted to the holder 22 by the manipulation of the head 30. Inasmuch as one complete turn of the element 28 is the equivalent of the twenty-five degrees into which the transverse face of the head 30 is divided, and inasmuch as the threads of element 28 are forty to the inch; one complete turn of the head 30 in either direction

will move the tool 24 one-fortieth of an inch. The movement of the head 30 one degree in either direction in effect indicates that the tool 24 has moved one-thousandth's of an inch. The upper end of the post 18 is provided with a lug 35. The distance "over all" of the lugs 23 and 35, when the cutting 100 110

point of the tool 24 touches the face 17 of the post 13 as arranged on the pivot pin 12, is a certain or "known" dimension. As hereinbefore stated, when the post 13 is arranged on the pin 12, the face 17 will aline with the axial center of the said pin 12. Inasmuch as there is a "known" dimension when the point of the cutting tool 24 is in a plane coincident with the axial center of the pin 12, further movement of the tool 24 to either side of the axial center of the pin 12 may be ascertained by noting the change which will be shown by a re-measurement of the distance "over all" of the lugs 23 and 35. A set screw 34 serves to hold the tool holder adjusted in different positions.

As shown in Fig. 4 of the drawing, the tool 24 is moved to the left of the axial center of the pin 12, and in such position of the tool, when the device in its entirety is moved about the pivot pin 12, the working face of a grinding wheel may be concaved. The position of the tool 24 as shown in Fig. 5 is such that when the device in its entirety is moved about the pivot pin 12, the working face of a grinding wheel may be convexed. It will be manifest that the working face of a grinding wheel may be concaved or convexed accurately in accordance with specified dimensions; that the device embodies means with which such results may be readily accomplished.

What is claimed as new is:-

35 1. A grinding fixture embodying a diamond-tool, a pivot having one face thereof in alinement with the axial center of said pivot, means for effecting movement of said tool with relation to said face, and means per-

mitting the accurate determination of the 40 distance of movement of said tool for the accurate setting of said tool, the last mentioned means including relatively separable measuring lugs.

2. A grinding fixture embodying a diamond-tool, a pivot on which the fixture as a whole moves, a base, a post having a measuring lug, the said post being positioned on said base, a slidable holder for the diamond-tool, said holder having a measuring 50 lug movable with relation to said first mentioned lug, as and for the purpose specified.

3. A grinding fixture embodying a diamond-tool, a pivot, a slidable holder for said tool, a post having one face thereof in alinement with the axial center of said pivot, means including a micrometer for effecting the movement of said holder to different positions and means for securing the holder in different positions.

4. A grinding fixture which has pivotal movement comprising, a base, a pivot pin carried by said base, a post adapted to be located on said pin, said post having a face thereof in alinement with the axial center 65 of said pivot pin, a second post secured to said base, a holder mounted for sliding movement, a lug on the last mentioned post, a lug on said holder, a micrometer adjusting element operable in said last mentioned post, 70 said element being engageable with said holder for moving the same, a cutting tool carried by said holder and means for securing said holder against movement as and for the purpose specified.

In testimony whereof I have affixed my signature.

JOSEPH DUPLESSIE.
